[57] ABSTRACT

The tie-back collar of an inner casing is provided with a protector sleeve which is sealed in place and supported against rotation. To temporarily abandon the well after the annulus between the inner and an outer string has been fully cemented up past the tie-back collar, the inner and outer strings are severed with a casing cutter above the tie-back collar. When tying back into the well, a spear may be used to retrieve the remaining part of the protector and a thread-in or stab-in tie-back sub may then be connected to the inner string to reestablish communication with the well.

TIE-BACK SYSTEM FOR UNDERWATER COMPLETION

BACKGROUND OF THE INVENTION

The U.S. Pat. of Pitts et al, No. 3,405,763, issued Oct. 15, 1968 describes a down-hole, pawl-tripped, expandable ring-type casing hanging system substantially as sold by the assignee of that patent, Gray Tool Company of Houston, Tex. as its "DJ" line of well completion equipment. (See pages 2104-2107 of Composite Catalog of Oilfield Equipment and Services, 1968-69 Edition, Gulf Publishing Co., Houston, Tex.) That well completion apparatus is fairly explicitly described in those publically available documents and so will not be described in such detail here. Suffice it to say here drawing particular attention to FIG. 9b of the Pitts et al patent that the system provides for hanging an inner string of pipe with respect to an outer string of pipe by means of incorporation of a fluted hanger in the inner string, which seats on a down-hole internal shoulder in the bore of the outer string via a bearing ring which is initially stowed in an inactive mode on the hanger, then released for self-expansion through the action of a pawl-tripping arrangement.

One feature of the "DJ" equipment which has found acceptance in the marketplace is the provision of an unscrewable joint at the upper end of the hanger, which is for allowing easy recovery of all of the inner string, above the hanger even after cementing, should temporary abandonment and capping of the well be found desirable.

(Temporary abandonment is utilized in the petroleum well drilling industry to permit maximum use of equipment during the period of drilling of exploration and field or formation definition wells, before a decision has been reached whether there is enough recoverable subterranean petroleum and attendant products to make completion, production, separation and gathering economically feasible.) When a decision is made to complete the abandoned well a threaded or stabbable sub is reconnected to the hanger. This procedure is described in the Pitts et al patent in relation to FIGS. 10-12 thereof. Additional designs of tie-back subs usable with the "DJ" hangers are illustrated in the U.S. Pats. of Quebe et al, No. 3,400,950, issued Sept. 10, 1968 and Harwell, Jr., U.S. Pat. No. 3,456,729, issued July 22, 1969, both assigned to Gray Tool Company.

The unscrewable joint referred to above also comes into use during cementing of the inter-string annulus since circulating parts for washing out excess cement are provided on the hanger. These may be exposed by partly unthreading the sub from the hanger at said unscrewable joint.

In the cementing operation, cement is forced down the bore of the inner string with a following plug until returns from the inter-casing annulus are visible at the surface (i.e. issue from piping connected to that annulus at the surface). Then the circulation parts are opened and washing fluid is circulated out the ports and up to the surface for a sufficient period of time (e.g. 2 hours) that the washing fluid is no longer turbid with diluted cement, indicating that the cement in the annulus has been washed out down to the level of the circulating ports and probably to a level somewhat therebelow. However with methods currently in use by most operators it cannot be known with certainty that some cement has not been left above the desired level due to channeling of the washing fluid through the cement. If such cement is left and is allowed to harden, the tie-back sub may be locked in place so it can neither be backed out nor fully reconnected.

In the U.S. Patent application of John Slack and Willis Marvin Phipps, Ser. No. 876,809, filed Nov. 14, 1969, there is disclosed a tie-back connection including a sub, spaced further above (for instance 6-25 feet above) the hanger. After an inter-casing string annulus has been cemented to a level above a down hole hanger in the inner string, a sub is partly backed out of an upward extension of the hanger to expose circulating ports having conduits channeling washing fluid to substantially below the sub-to-hanger connection and preferably to the level of the hanger flutes, to provide for disconnection and

reconnection of the sub (for temporary abandonment of the well) and for cutting the inner casing below its hang point (for recovery of the string in a permanent abandonment of the well). In one embodiment the washing fluid conduits are individual pipes; in another, they include a single tube surrounding an upward extension of the hanger.

However, there are instances where, due to governmental regulations, operator predilection or upon the recommendation of petroleum geologists, full cementing of certain inner/outer casing string annuli is employed.

SUMMARY OF THE INVENTION

The present invention provides ways and means for providing permanent or temporary abandonment (with provision for subsequent tie-back and completion) of particularly, but not exclusively, underwater petroleum wells.

In making use of the invention the tie-back collar of an inner casing is provided with a protector sleeve which is sealed in place and supported against rotation. To temporarily abandon the well after the annulus between the inner and an outer string has been fully cemented up past the tie-back collar, the inner and outer strings are severed with a casing cutter above the tie-back collar. When tying back into the well, a spear may be used to retrieve the remaining part of the protector and a thread-in or stab-in tie-back sub may then be connected to the inner string to reestablish communication with the well.

The principles of the invention will be further hereinafter discussed with reference to the drawings wherein preferred embodiments are shown. The specifics illustrated in the drawings are intended to exemplify, rather than limit, aspects of the invention as defined in the claims.

BRIEF DESCRIPTION OF THE DRAWINGS

IN THE DRAWINGS

FIG. 1 is a longitudinal sectional view of a partly completed petroleum well utilizing equipment of the present invention;

FIG. 2 is a longitudinal sectional view of the well at a later stage wherein steps toward temporary abandonment of the well have been initiated;

FIG. 3 is a longitudinal sectional view of the well showing a further step in temporary abandonment;

FIG. 4 shows the well in longitudinal section after temporary abandonment, with initial steps toward reconnection with the well;

FIG. 5 is a fragmentary longitudinal sectional view of the well showing retrieval of the dutchman of the spline assembly using a spear and stop collar; and

FIG. 6 shows the well in longitudinal section following reestablishment of connection with the well, at a stage where the well is ready for normal completion.

GENERAL DESCRIPTION OF THE WELL

For the purpose of most efficient explanation of the invention to persons skilled in the art, a typical casing program will be described in this section. It should be kept in mind, however, that this is but one typical manner in which the principles of the invention may be efficiently put to work. Use of the invention in other programs will be apparent to those skilled in the art from the following discussion.

In the example, the casing program includes use of:

30 inch O.D. conductor pipe to 300 feet,

20 inch O.D. outer casing to 500 feet,

13 1/2 inch O.D. next inner casing to 4,000 feet,

9 1/2 inch O.D. next inner casing to 9,000 feet,

and 7 inch O.D. liner to total depth.

Also in this example, the distance from the rotary table to the water line is 40 feet and the distance from the rotary table to the mud line is 115 feet. In other words, the well is being drilled in water 75 feet deep. The system described, in the presently preferred embodiment, provides for temporary abandonment of the well at the mud line with provision for tying back to the surface for production.

As initial steps in drilling the well 10, the rig is positioned over the site and the conductor pipe 12 (FIG. 2) is driven into the bottom until successive blows no longer result in increased penetration. This conventional technique is termed "driving until refusal" and is normally stated in terms of number of blows needed to increase penetration by 1 foot. In the present instance, a refusal at 350 blows/foot might, for instance, be achieved after 185 feet of conductor pipe had been forced into the subsea earth, leaving 115 additional feet of conductor pipe extending from the mud line up to the rotary. At this point about 20 feet of the upper end of the conductor pipe can be cut off so that the cut-off conductor pipe will terminate about 20 feet above the water line and about 20 feet below the rotary.

Next, well drilling is begun through the conductor pipe 12 to e.g. 500 feet below the rotary at a diameter of 26 inches. The 20 inch casing 14 is then run with conventional centralizers 15 to centralize the 20 inch casing with respect to the 30 inch conductor pipe and the hole, to facilitate cementing, and casing cutting during temporary abandonment. In this example the annulus 16 between the hole and the 20 inch casing and between the 30 inch conductor pipe and the 20 inch casing is cemented to the surface (i.e. until cement 18 overflows from the cut-off upper end of the 30 inch conductor pipe).

When the cement 18 has set, the 20 inch casing 14 may be cut off above where it emerges from the upper end of the 30 inch conductor pipe and a 20 inch casing head and 20 inch blow-out preventer may be temporarily installed to provide for well control during the next drilling step.

In the next step, the well is drilled to 4,000 feet at a diameter of 17 1/2 inches through the 20 inch equipment. Then the 13 1/8 inch casing string 22 is run. This casing string incorporates tie-back provision equipment 24 (FIG. 1) which will be described in further detail below.

It is important when practicing the invention to predetermine the location of the equipment 24, so that upon running the 13 1/8 inch casing string 22 into the well the equipment 24 will be near the mud line. It is expected that operators will record the actual positioning for later use during temporary abandonment and tie-back. Centralizers 25 are shown provided on the string 22 above and below the equipment 24.

After the 13 1/8 inch casing string 22 is run, the annulus 26 between the casing string 22 and the hole and between the casing string 22 and the 20 inch casing string 14 is cemented to the surface. Tension is maintained on the upper end of the casing string 22 until the cement 28 has set. (Tension setting is a conventional practice.)

In this particular example, the next step involves cutting of the 13 1/8 inch string above where it emerges from the 20 inch casing string, removal of the 20 inch casing head and 20 inch B.O.P. and installation of a 13 1/8 inch casing head 32 on the upper end of the 13 1/8 inch casing string with support being transferred to the upper end of the 20 inch casing 14 via a 20 x 13 1/8 x 1 1/8 inches split base plate 34. The base plate 34 is circumferentially welded to the head at 36. Associated blow-out preventer equipment 38 is installed on the head 32 and conventionally tested.

(The decision to use a first, larger diameter casing head and an associated blow-out preventer when drilling for the surface casing, then to replace this with a smaller diameter casing head and associated blow-out preventers, is one based on pressure ratings of the equipment and expected pressures to be encountered. There are instances where it is possible to use one set of larger diameter head and control equipment throughout the drilling stages, or such equipment with additional equipment being installed within or upon the larger diameter first casing head.)

As a next step, the well is drilled through the 13 1/8 inch equipment to a depth of e.g. 9,000 feet at a diameter of 12 1/4 inches for receipt of the 9 1/8 inch O.D. casing string 40 which is then made up and run.

While maintaining the 9 1/8 inch casing string 40 in tension, the annulus 46 between the casing 40 and the hole and 75

between the casing 40 and the 13 1/8 inch casing is cemented then circulated free of cement down to the level below the disconnectible joint 48 of the equipment 44. The tie-back equipment 44 of the 9 1/8 inch string is located about 30 feet below the tie-back equipment 24 of the 13 1/8 inch string.

Using conventional equipment and techniques, after the cement 50 has set, the 9 1/8 inch casing may be hung in the casing head 32 using a hanger 52. Then, after actuation of the hanger and testing, the blow-out preventers may be removed, a casing bonnet, a tubing head, and yet smaller diameter blow-out preventers installed and tested, in that order.

The hole is then drilled to total depth through the smaller diameter (e.g. 10 inch) blow-out preventers and a 7 inch liner 54 run into the well within the 9 1/8 inch casing string and set at 56 with a liner hanger.

The well is then ready for perforation at the level(s) from which production of desired fluids seems promising. Testing of the production possibilities can then be conducted in the usual fashion.

If the well proves to be not worth producing from, it may be permanently abandoned after recovering all of the equipment from it as is feasible. In the present instance, this can be done by setting cement plugs at the appropriate depths removing the surface well head equipment, moving the rig off location, attaching salvage lines to the conductor pipe, to the assembly 24 and to the assembly 44 and then shooting off the casing at a level below the equipment 44.

However, if the well looks like it could be of production interest, but is to be temporarily abandoned pending the drilling of additional wells, the tie-back system 24 of the present invention comes into play.

DETAILS OF THE TIE-BACK SYSTEM 24

With reference to FIG. 1, the tie-back system includes a plurality of interconnected tubular parts, a basic one being the tie-back collar 70 which at its lower end threadably connects with the casing string 22 in which the system 24 is interposed.

40 The upper end of the system 24 is integrated with the casing string 22 via a sub 72 with a threaded box 74. By preference, the collar 70 and sub 72 are not made integrally, so that the total length of the system 24, and in particular of the central section 76 thereof can be made of various lengths in accordance with customer requirements. As will be apparent, this mode also allows reuse of the upper portion of the housing of the system. The central section 76 of the housing of the system is shown comprising a nipple of casing pipe, for instance, 8 feet long and exteriorly threaded at both ends. An internally threaded collar 78 connects the collar 70 and central section 76; an internally threaded collar 80 connects the sub 72 and the central section 76.

55 The bore 82 of the tie-back collar 70 is generally cylindrical, particularly at 84 near its upper end 86 and at 88 below the band of internal threading 90 in the bore. The threading 90 is preferably supplied as Acme threads. Somewhat below the band of threading 90, the bore cylindrical surface 88 is interrupted by a circumferentially extending, upwardly facing shoulder 92.

60 The bore 94 of the sub 72, intermediate the axial extent of the sub 72, is radially enlarged in a sense to produce a downwardly facing shoulder 96 and a bore portion 98 of larger diameter from the shoulder 96 to the lower extent of the sub 72.

65 Thus, the housing 100 of the equipment 24 includes the sub 72, the collar 80, the central section 76, the collar 78 and the tie-back collar 70.

Within the housing 100 is shown received a tubular protector sleeve 102 and a tubular cementing sleeve 104. The upper end region of the cementing sleeve is received in the enlarged portion 98 of the sub 72 bore, with the cementing sleeve 104 upper end 106 being circumferentially welded to the shoulder 96 at 108.

The tubular protector sleeve 102 has a lower end portion received in the bore of the tie-back collar 70 with a lower end 110 seated on the shoulder 92. At raised circumferential bands, the exterior of the sleeve 102 is circumferentially grooved at two axially spaced levels facing the tie-back collar bore portion 88 and at two axially spaced levels facing the tie-back collar bore portion 84, to receive resilient, annular sealing rings 112 and 114 for sealing with the portions 88 and 84.

The cementing sleeve 104, below its emergence from the bore of the sub 72 is provided with a threaded lateral opening 116 which is stopped with a threaded plug 118. The protector sleeve 102, between the two sets of sealing rings 112 and 114 is similarly provided with a threaded lateral opening 120 which is stopped with a threaded plug 122.

It should now be noticed that the lower end region of the cementing sleeve 104 is received in the upper end portion of the bore of the protector sleeve 102. The bore of the protector sleeve 102 is generally cylindrical, but in the upper end region thereof, it is radially enlarged to provide an upwardly facing shoulder 126. Thereabove for a short distance, vertical spline grooves 128 are cut on the bore. Above the grooves 128, the bore of the protector sleeve 102 is cylindrically enlarged in the region 127 to the diameter of the root circle of the grooves 128. The lower end of the cementing sleeve 104 is shown exteriorly notched to provide vertical spline fins 130 extending up the exterior of the cementing sleeve a short distance. Above the upper extents of the spline fins 130, the cementing sleeve is circumferentially grooved to receive a resilient sealing ring 132 which sealingly engages the smooth portion 127 of the bore of the protector sleeve 102. When assembled as shown, the lower ends of the fins 130 enter the upper ends of the grooves 128, thus interdigitating the spline. However, since the lower end of the cementing sleeve still lies above the shoulder 126 of the protector sleeve, the spline portions are designed for greater interpenetration at a later stage (which will be later discussed in connection with FIG. 3).

The purpose of the spline 128/130 is to lock the protector sleeve against rotation (because of the fixation of the cementing sleeve to the sub 72 at 108) during drilling and to allow a lower portion of the cementing sleeve to drop down a few inches and get out of the way as casing cutting steps are begun for temporary abandonment of the well (FIG. 3).

In most instances, the entire assembly 24 as described including the housing 100, the protector sleeve 102 and the cementing sleeve 104 can be made up in a manufacturing plant and shipped as an assembled unit for insertion in a particular size casing string, in the instance shown a 13 1/8 inch O.D. casing string. The assembly bore 136, principally comprising the inwardly exposed parts of the bores of the sub 72, the cementing sleeve 104, the protector sleeve 102 and the tie-back collar 70, has the same diameter as the bore of the casing of the casing string 22 in which it is interposed.

During assembly, the part of the bore of the tie-back collar 70 which will be covered by the protector sleeve is hand packed with heavy grease 140. The resilient sealing rings at each end of the protector sleeve contain this body of grease between them. The pipe plug 122 is removed during assembly to allow excess grease to bleed from the contained space. After assembly the plug 122 is reinstalled.

The main purpose of the threaded plug 118 is to allow fluid pressure testing of the threaded joints 142, 144, 146 and 148 and the weld 108 after assembly. During this testing, using a test fluid under pressure admitted from within the cementing sleeve through the opening 116, the seal at 132 prevents escape of the test fluid into the bore of the 13 1/8 inch casing string 22. After testing, the test fluid is drained out the opening 116 and the plug 118 is reinstalled.

TEMPORARY ABANDONMENT OF THE WELL

With reference to FIG. 2, if the well is to be temporarily abandoned, communication between subterranean pressure and the surface is interrupted, e.g. by installing a wireline

bridge plug 150 above the uppermost perforated interval or above the 7 inch liner 54 liner hanger 56. Sufficient cement 152 is spotted on top of the bridge plug 150 to keep it in place. In recommended practice for deep wells, a second cast iron bridge plug 154 may be set at about 3,000 feet down from the drilling platform. Then the blow-out preventer stack may be disassembled from the casing head 32 and buoys attached to the conductor pipe via buoy lines 156 secured near the mud line.

10 Next the 9 1/8 inch casing may be cut at a level below where it is hung in the head 32. During this stage, the tubing head preferably remains in place on the casing head bonnet on the casing head 32 to prevent an upward jump of the casing hanger and bonnet when the 9 1/8 inch casing is separated.

15 After the casing is cut, the hanger, bonnet and tubing head may be removed with the axially short, cut-off upper end of the 9 1/8 inch casing. A spear 158 can then be used to remove the tie-back sub of the equipment 44 and the 9 1/8 inch dutchman (i.e. that part of the 9 1/8 inch casing lying between the cut and the tie-back sub of the assembly 44).

20 However, as an alternative to cutting the 9 1/8 inch casing, if the cement level holding the 9 1/8 inch casing will allow the casing to stretch, the tubing head and casing bonnet may be

25 removed and the hanger for the 9 1/8 inch casing spot welded to that casing. A 9 1/8 inch casing spear 158 can then be used to pick up and rotate the 9 1/8 inch casing to the right to back the tie-back sub of the equipment 44 out of the tie-back collar of the equipment 44. This (using the equipment of the above-mentioned Pitts et al patent) will require about 14 turns to

30 release the sub. Thus, the hanger, 9 1/8 inch casing between the hanger and the tie-back sub, and the 9 1/8 inch tie-back sub may be withdrawn from the well as a unit.

35 Regardless of which way the inner string is disconnected down to the level of its tie-back means, the next step of the method disclosed herein is severing of the remaining outer strings and cement annuli at a level intermediate the axial extent of the system 24.

As noted hereinabove, recording of the level of the system

40 24 when it is installed is important. At the present stage, a multi-string casing cutter 160 (an acceptable one is manufactured by Brown Oil Tools, Inc. of Houston) is lowered in the bore of the 13 1/8 inch casing string 22. When the cutter 160 is located within the equipment 24, with the blades 162 thereof

45 radially adjacent the cementing sleeve as detected by a conventional collar locator of the cutter and as confirmed by data previously recorded as to the level of the apparatus 24, the blades 162 of the cutter 160 are actuated to successively cut through the cementing sleeve 104, the housing 100, central section 76, cement in the annulus between the 13 1/8 and 20 inch casing strings, the 20 inch casing string, the cement in the annulus between the 20 inch casing string and 30 inch conductor pipe, and through the 30 inch conductor pipe. It should

50 here be noted that in the preferred embodiment as shown, as soon as the cementing sleeve has been cut through, its lower portion ("dutchman") below the cut, drops down a few inches further interdigitating the spline 128, 130 the lower end of the cementing sleeve dutchman coming to rest on the shoulder 126 of the protector sleeve. Thus, the spline prevents rotation

55 of the cut-off lower part of the cementing sleeve and allows this dutchman to drop down out of the way of the cutter blades which then expand to begin cutting the nipple 76. Otherwise, the dutchman could rotate with the cutter causing malfunctioning, cocking of the dutchman or damage to other parts. Everything above the cut may then be hauled to the surface. It is most convenient to further cut this composite of cement and casings into 15-20 foot sections as it is hauled up.

60 Then a buoy 166 may be secured to the buoy lines and an abandonment cap 168 run down on drill pipe and placed over the cut-off upper end 170 of the well. It is recommended that this cap 168 have a fishing neck 172 welded in its center and

65 lift pad eyes 174 provided at its edges. The cap is shown provided with a recommended 200 feet or so of junk drill pipe

70 176 secured to it and hanging from it into the well from the

fishing neck to act as a stinger for stabbing (FIG. 4) and to provide additional weight and stability for the cap 168.

To provide for the possibility that the buoy may become lost during the period that the well is temporarily abandoned, it is preferred that a sonic "pinger" locating device (commercially available) be mounted on the cap.

REESTABLISHMENT OF COMMUNICATION WITH THE TEMPORARILY ABANDONED WELL

With further reference to FIG. 4, when reestablishment of communication with the temporarily abandoned well is desired, the buoy is removed, an overshot 180 is lowered on drill pipe 182 and, with diver assistance if needed, stabbed onto the neck 172 of the abandonment cap 168. The cap is then withdrawn to the surface with the drill pipe 182.

Next a 13 $\frac{3}{8}$ inch spear 184 provided with a stop collar 186 is run into the remaining lower part of the assembly 24 and engaged with the protector sleeve 102. (The stop collar 186 is used for accurately vertically positioning the spear based on knowledge of the length of the upper part of the cementing sleeve retrieved when the well was temporarily abandoned.) The spear is recovered to the surface, bringing with it the dutchman of the cementing sleeve 104 and the protector sleeve 102 with adherent grease 140. The grease has served to prevent mud and other fluids from clogging or corroding the space between the cementing sleeve and the tie-back collar.

Retrieval of the cementing sleeve dutchman and the protector sleeve exposes the cylindrical surfaces and the acme threads of the bore of the tie-back collar so that a tie-back sub may be connected to the tie-back collar.

A tie-back sub 190 is made up on the lower end of a riser 192 of 13 $\frac{3}{8}$ inch casing and lowered to the upper end of the cut-off well. The sub 190 is provided with external acme threading corresponding to that of the tie-back collar 70. Using diver assistance if needed, the 13 $\frac{3}{8}$ inch tie-back sub 190 is stabbed into the 13 $\frac{3}{8}$ inch tie-back collar and the riser rotated slowly (e.g. 14 turns using hand tongs) until the threads are made up with desired torque. If operations or foreign matter have somehow damaged the internal threading in the bore of the 13 $\frac{3}{8}$ inch tie-back collar, a stab-in type tie-back sub e.g. as described in the aforementioned U. S. Pat. of Quebe et al No. 3,400,950 may be substituted for the sub 190.

Then a casing head 194 may be installed on the upper end 45 of the 13 $\frac{3}{8}$ inch riser 192 and a conventional pressure test conducted to determine that the 13 $\frac{3}{8}$ inch casing string has been tied-back into with integrity. When this has been established, successive steps may include:

Running a 9 $\frac{1}{2}$ inch casing riser 196 with a tie-back sub 198 50 for tying into the equipment 44 in accordance with Pitts et al, aforementioned;

Grouting the 13 $\frac{3}{8}$ $\times$ 9 $\frac{1}{2}$ inch casing annulus 200 with cement 202 to the surface, e.g. using a small diameter grouting string lowered into the annulus and gradually raised during the cementing;

Hanging the 9 $\frac{1}{2}$ inch casing with respect to the head 194 using a hanger 204, then installing a bonnet 206 and tubing head 208 (aforementioned Composite Catalog, pages 2116 and 2117);

Installing a blow-out preventer stack 210; then going into the well with a bit 212 and drilling out the cast iron bridge plugs.

The well is then ready to be conventionally completed, e.g. 65 with packers, tubing, a tubing head bonnet and the associated valving and control devices of a Christmas tree.

Departure from the details set forth above to explain the principles of the invention is possible. However, it is believed that those skilled in the art will appreciate the comprehensiveness of the above discussion and will be better enabled by it to understand how the invention may be effectively utilized.

In its essence, the invention provides ways and means for temporarily abandoning and tying back into the casing string of a well casing string which lies between a fully cemented an-

nulus (between it and an outer casing) and a partly cemented or uncemented annulus (between it and an inner casing).

I claim:

1. A petroleum well casing tie-back system comprising: a tubular housing having an upper end and a lower end, securing means on said housing upper and lower ends for interposing said housing in a casing string of particular inner and outer diameter;

said housing having means defining an internal throughbore; means on said housing in said throughbore intermediate said upper and lower ends of said housing defining a band of cooperative securement elements for subsequent securing reception of a tubular tie-back sub; tubular sleeve means coaxially received in said throughbore, said sleeve means extending axially over said band of cooperative securement elements; securement means on said sleeve means and on said housing securing said sleeve means against rotation with respect to said housing, said sleeve means having a throughbore of a diameter at least as great as said particular inner diameter whereby a petroleum well may be further drilled through said system while said sleeve means protects said band of cooperative elements against wear damage thereto; at least part of said tubular sleeve means being axially retractable from extending axially over said band of cooperative securement elements for exposing the cooperative securement elements for said subsequent securing reception of a tubular tie-back sub; the housing comprising a sub, an intermediate tubular section having an upper end and a lower end and a tie-back collar having an upper end; said band of cooperative securement elements being provided on said tie-back collar; means connecting the sub to the upper end of the intermediate tubular section, means connecting the upper end of the tie-back collar to the lower end of the intermediate tubular section; said intermediate tubular section being adapted to be severed in a central portion thereof to expose said tubular sleeve means for axial retraction; said tubular sleeve means comprising an upper, cementing sleeve and a lower, protector sleeve each having a throughbore defining in composite the throughbore of said tubular sleeve means; a lower portion of said cementing sleeve being received in an upper portion of the throughbore of said protector sleeve; means defining an upwardly facing shoulder on said protector sleeve in the throughbore thereof, said shoulder normally being axially spaced below and in line with the lower extent of said cementing sleeve; connecting means between the upper end of said cementing sleeve and said housing fixedly, connecting the upper end of said cementing sleeve to said housing above said central portion; cooperating spline means extending vertically on the lower end of said cementing sleeve and on said protector sleeve in the throughbore thereof above said shoulder; said cementing sleeve normally having a central portion thereof disposed radially adjacent said central portion of said housing and adapted to be severed immediately prior to severing of said housing central portion, whereby a dutchman of said cementing sleeve created by the severing of said cementing sleeve at said central section thereof may drop out of the way and land on said shoulder; means defining an internal shoulder on said housing below said central section thereof and means defining an external shoulder on said protector sleeve adapted to rest upon and receive support from said internal shoulder to support said protector sleeve and the dutchman of said cementing sleeve in said housing below said central section following severing of said cementing sleeve and said housing at their respective central sections.

2. A petroleum well casing tie-back system comprising: a tubular housing having an upper end and a lower end, securing means on said housing upper and lower ends for interposing said housing in a casing string of particular inner and outer diameter;

said housing having means defining an internal throughbore; means on said housing in said throughbore intermediate said upper and lower ends of said housing defining a band of cooperative securement elements for subsequent securing reception of a tubular tie-back sub; tubular sleeve means coaxially received in said throughbore, said sleeve means extending axially over said band of cooperative securement elements; securement means on said sleeve means and on said housing securing said sleeve means against rotation with respect to said housing, said sleeve means having a throughbore of a diameter at least as great as said particular inner diameter whereby a petroleum well may be further drilled through said system while said sleeve means protects said band of cooperative elements against wear damage thereto; at least part of said tubular sleeve means being axially retractable from extending axially over said band of cooperative securement elements for exposing the cooperative securement elements for said subsequent securing reception of a tubular tie-back sub; further comprising circumferential sealing ring means provided between said housing and said tubular sleeve means both above and below said band of cooperative securement elements; an extensive body of fluid packing material filling axially between the sealing ring means, and radially between the housing and the tubular sleeve means.

3. The system of claim 2 wherein the band of cooperative securement elements comprise helical threading.

4. The system of claim 2 wherein the housing comprises a sub, an intermediate tubular section having an upper end and a lower end and a tie-back collar having an upper end; said band of cooperative securement elements being provided on said tie-back collar; means connecting the sub to the upper end of the intermediate tubular section, means connecting the upper end of the tie-back collar to the lower end of the intermediate tubular section; said intermediate tubular section being adapted to be severed in a central portion thereof to expose said tubular sleeve means for axial retraction.

5. The petroleum well casing tie-back system of claim 5 wherein the packing consists of heavy grease; said tubular sleeve means being provided with means defining a threaded opening therethrough normally lying axially between said seal-

ing ring means, and a threaded plug normally stopping said opening, said plug being removable for bleeding of said grease during assembly of said system.

6. A method for temporarily abandoning a petroleum well having an outer string of casing comprising:

providing the well with an inner, concentric string of casing having a band of internal tie-back sub securement means in the bore thereof for subsequent receptive securement of a tie-back sub and a non-rotatable sleeve covering the securement means;

cementing the annulus between the inner and outer casing strings up past the level of said securement means; allowing the cement to set;

severing the inner and outer strings of casing above said securement means leaving said sleeve covering said securement means; and capping the well.

7. A method for temporarily abandoning, then tying back into, a petroleum well having an outer string of casing comprising:

providing the well with an inner, concentric string of casing having a band of internal tie-back sub securement means in the bore thereof for subsequent receptive securement of a tie-back sub and a non-rotatable sleeve covering the securement means;

cementing the annulus between the inner and outer casing strings up past the level of said securement means; allowing the cement to set;

severing the inner and outer strings of casing above said securement means leaving said sleeve covering said securement means;

withdrawing the severed elements; and capping the well for temporary abandonment; subsequently, on capping the well; withdrawing said sleeve

to expose said securement means; making up a casing riser with a tie-back sub on the lower end thereof; lowering said riser toward the well; stabbing said tie-back sub into the well and securely engaging the sub with said securement means to reestablish communication with the inner casing string of the well.
